US00D794770S

(12) **United States Design Patent** (10) **Patent No.:** **US D794,770 S**
(45) **Date of Patent:** **** Aug. 15, 2017**

(54) **DRUG DELIVERY PUMP**

(71) Applicant: **UNITRACT SYRINGE PTY LTD.**,
Sydney (AU)

(72) Inventors: **Kun-Chi Wu**, Princeton, NJ (US);
Lawton Laurence, Phoenixville, PA (US)

(73) Assignee: **Unitract Syringe Pty Ltd**, Sydney (AU)

(**) Term: **15 Years**

(21) Appl. No.: **29/531,569**

(22) Filed: **Jun. 26, 2015**

(51) LOC (10) Cl. **24-01**

(52) U.S. Cl.

USPC **D24/108**

(58) **Field of Classification Search**

USPC D24/107, 108, 111–113, 185, 188
CPC A61M 5/20; A61M 5/30; A61M 5/142;

(57) **CLAIM**

The ornamental design for a drug delivery pump, as shown and described.

DESCRIPTION

FIG. 1 is a back view of a drug delivery pump, showing our novel design;

FIG. 2 is an isometric top view thereof;

FIG. 3 is a front view thereof;

FIG. 4 is a top view thereof;

FIG. 5 is a bottom view thereof;

FIG. 6 is a right side view thereof; and,

FIG. 7 is a left side view thereof.

Broken lines in the drawings illustrate portions of the drug delivery pump that form no part of the claimed design.

1 Claim, 6 Drawing Sheets
